[73] Assignee: **Hyundai Electronics Ind. Co., Ltd.**, Kyoungki-do, Rep. of Korea

[57] CLAIM

[*] Notice: This patent is subject to a terminal disclaimer.

[**] Term: **14 Years**

[21] Appl. No.: **29/101,382**

The ornamental design for a foldable wireless telephone housing, as shown and described.

[22] Filed: **Mar. 2, 1999**

DESCRIPTION

[51] LOC (7) Cl. **14-03**

FIG. 1 is a perspective view of the foldable wireless telephone housing in a closed position;

[52] U.S. Cl. **D14/138**

FIG. 2 is a right side plan view thereof in the closed position;

[58] Field of Search D14/137, 138,

FIG. 3 is a top plan view thereof in the closed position;

D14/147-148, 247-248, 250, 240, 140-142;

FIG. 4 is a rear plan view thereof in the closed position;

379/433, 434, 419, 420, 428, 440; 455/550-575,

FIG. 5 is a bottom plan view thereof in the closed position;

90

FIG. 6 is a left side plan view thereof in the closed position;

FIG. 7 is a front view thereof in the closed position;

FIG. 8 is a perspective view of the foldable wireless telephone housing in an open position;
